UNITED STATES PATENT OFFICE

WENZEL KÖNIG, OF LEIPZIG, GERMANY

SHOWER ROSE

Application filed June 5, 1930, Serial No. 459,375, and in Germany July 24, 1929.

This invention relates to a special construction of a shower rose, which enables a very fine distribution of the water ejected by a number of absolutely separate sprays. Such shower roses are often termed incorrectly nozzles or nozzle heads.

The formation of the individual sprays is caused in that within a casing (handguard) 10 conical rings, that is rings with a conical outer surface, are arranged, which are inserted concentrically one in the other, unsupported, projecting stepwise, form an outer wall and are provided on the conical outer surface thereof with slotlike channels in axial direction.

The individual rings are held in position by a common holding device (screw), which engages in the innermost ring.

The peculiar constructional form of the shower rose ensures an accurate direction indication for each individual jet, which is caused by the concentricity of the rings.

As compared with the known devices, serving the same purpose, for finely distributing the water and the like in jet from the new shower rose presents the advantage that the water or the like flows out in a larger number of fine jets, separate the one from the other, mist or film-like, whereas with the showers hitherto employed, in which the water was ejected by torsion, by impact or by compressed air (especially with those with coarse distribution), the water flows together to form large drops on the outer side of the rose.

A further advantage consists in the easy possibility of cleaning the separate rings, so that coggings can be overcome without difficulty.

In the known constructions of showers or nozzles such cleaning is difficult and wastes time. The discharge holes of the rose are enlarged by inexperienced persons with pointed objects so that the further use of such water distributors, as showers, nozzles and the like, is almost impossible, or they only fulfill their purpose in an imperfect manner.

The desired degree of fineness of the atomizing is caused by the depth and number of the channels arranged on the conical edges

of the ring, the degree of fineness being unlimited and the arrangement of any desired number of discharge openings on the smallest surface is possible.

The efficiency of the new shower rose depends upon the number and cross section of the holes and the pressure of the water discharged.

The shower roses may be made of non-rusting metals, hard rubbers, galalith, torit or other suitable material.

The invention further enables the regulation of the degree of fineness, as also the efficiency by elastic material (rubber) inserted between the rings, which material, according to the tension of the holding screw, is pressed more or less deeply into the channels and alters their cross section.

Consequently the invention presents a considerable technical advance, which is of great commercial interest.

Two embodiments of the invention are illustrated by way of example in the accompanying drawing in which:

Fig. 1 shows one form of construction in longitudinal section.

Fig. 2 is a front view of Fig. 1.

Fig. 3 shows details.

Fig. 4 shows the second form of construction.

The known connecting socket *a* has discharge holes *b* arranged concentrically around the holding device. Between the head *d* of the holding device (screw) *c* and a ring-shaped extension *e* situated on the inner side of the handguard *f* a set of rings *g* with conical outer surfaces and inserted one in the other, projecting in steps, are arranged in such a manner that the pressure of the screw head *d* first acts on the smallest ring *g* and the extension *e* serves as a rest for the largest ring. The outer sides of these rings *g* are conically finely serrated so that channels *h* are produced, when the rings *g* are fitted together.

As soon as water under pressure flows out of the apertures *b* in the shower rose in known manner this water first encounters a resistance on the end surfaces *i* of the rings *g* facing it, so that the rings *g* tend to shift in

axial direction to the holding device *c*. The counter screw *c*, which presses the rings *g* onto their seat, opposes however this tendency so that only the channels *h* offer a passage for the water and cause fine distribution. The number of channels *h* and their size is determined according to the purpose of use, and the spraying range depends upon the conicity of the outer surfaces of the rings.

10. If necessary, an elastic layer *k*, made for example of rubber, may be inserted between the rings *g* (Fig. 4), which insertion, on the rings *g'*, *g''* shown by way of example in the drawing being compressed, causes a narrowing of the channels *h*.

15. I claim:—

1. A shower rose for hand showers, air moistening, gardens and the like, comprising in combination a casing having an inner 20 closing wall, and rings with conical outer surfaces arranged in said casing inserted concentrically one in the other and projecting unsupported in step shape and having on their conical outer surfaces axially extending 25 channels the conicity of said rings determining the spraying range of the jets.

2. A shower rose as specified in claim 1, comprising in combination with the rings, a holding device for said rings adapted to engage on the innermost of said rings.

30. In testimony whereof I affix my signature.
